UNITED STATES PATENT OFFICE

2,546,402

LIQUID FUEL BURNER, ATOMIZING TYPE

Frank W. Ofeldt, Carnet, Pa., assignor to Homestead Valve Manufacturing Company, Coraopolis, Pa., a corporation of Pennsylvania

Application March 31, 1947, Serial No. 738,316

8 Claims. (Cl. 158—4)

1

This invention relates generally to pressure atomizing oil burners and more particularly to pressure atomizing burners for producing a flame, the pressure combustion of which is in the shape of an annular vortex.

This invention is an improvement of the structure disclosed in Letters Patent No. 2,289,675 entitled Burner and issued to me on July 14, 1942.

Mechanically atomizing liquid fuel burners of the annular vortex type can produce an unevenly distributed flame even though the jet is accurately placed concentrically of the burner because of inaccuracies of commercial burner sets which produce a non-uniform conical spray pattern thereby having more fuel in the spray on one side of the cone than on the other side. When employing burners, that have an unevenly distributed flame, for the purpose of heating liquids passing through coils, it is difficult to obtain complete and uniform combustion and the heat transfer to the liquid within the coils is inefficient. Again an unbalanced flame frequently burns out some portion of the combustion chamber or heating coils due to the concentration of heat.

The principal object of this invention is to provide apparatus for centering the flame of a mechanical atomizing burner of the annular vortex type for the purpose of uniformly heating a spray solution in a spray generator.

Another object is to provide a novel and economical structure for producing a forced draft to support combustion of atomized liquid fuel.

Another object is to provide an improved arrangement for producing and guiding the flame of an atomized liquid fuel burner.

Another object is to provide an improved fire pot or flame guiding ring which acts in conjunction with a jet shield for producing the desired shape and propagation of an atomized fuel flame.

Other objects and advantages appear in the following description.

A practical embodiment illustrating the principles of this invention is shown in the accompanying drawing wherein:

Fig. 1 is a view in vertical section of a portion of a spray generator with parts broken away and showing the wind box and other burner improvements comprising this invention.

Fig. 2 is a view in horizontal section of the wind box and the blower.

Fig. 3 is a perspective view of the burner assembly shown in Fig. 1.

The spray generator structure shown in the drawings is completely shown and described in

2

application Serial No. 718,563, filed December 26, 1946, for Spray Generator. This vapor spray generator is supplied with a solution made up of a chemical and a liquid such as water which is metered to a heating zone where it is heated by a metered fuel and the amount of solution is correlated with the amount of fuel to generate a spray mixture of liquid and vapor of a liquid under pressure which when discharged from the nozzle produces a spray. The character of this spray may be varied by changing the correlation of the solution and fuel supplied to vary the liquid content, or the nozzle of the spray gun may be arranged to produce a relatively long spray stream or a completely flash atomized spray.

In the particular generator shown in Fig. 1 the metered solution is supplied through the pipe 5 to the lower section of the generator coils 6 which are wound in engagement with the sheet metal fire pot 7. The solution passes upwardly through the coil section 8 and other coil sections, not shown, in which the spray mixture is generated and from whence it travels through the pipe 10 to a spray gun where it is discharged. The heat transfer generating coils are enclosed within the casing 11 which is closed at the bottom and provided with a vent at the top for the discharge of the products of combustion. The generator casing 11, the chemical solution tank 12 and the fuel tank 13 are mounted in a row on the top of the wind box 14. In reality the wind box 14 is the chassis of the complete generator and its width is greater than the diameter of the casing 11. As shown in Fig. 2 a fifth wheel 15 is pivoted to the underside of the front of the wind box for attaching the formed plate 16 that carries the front wheels 17 that may be guided by a tongue and at the back a V-shaped plate 18 is secured to the wind box for supporting the back wheels 19.

An electric motor 20 is mounted on the rear of the wind box 14 and its shaft 21 extends forwardly to carry the pulley 22 and the fan or blower 23. The pulley 22 drives the belt 24 which is arranged to turn the pump pulley 25 that is provided with a crank to reciprocate the connecting rod 26 that operates positive displacement liquid solution and fuel pumps which are arranged to supply metered quantities of the liquid and fuel to the generator. The liquid solution is supplied through the pipe 5 and the fuel is withdrawn from the tank 13 through the pipe 27 to the fuel pump where it is metered and delivered through the pipe 28, the alleviator 29, the pipe 30 to the burner jet 31.

The blower 23 is disposed within the opening 32 of the hood 33 that connects at its lower end to the closed wind box 14. The blower 23 forces air down the hood into the wind box where it flows forwardly and through the opening 34 that is disposed in axial alignment with the fire pot 7 and the generator casing 11. A cylindrical air guide 35 defines the size of the opening 34 and extends upwardly into the fire pot 7. The upper perimetral edge of the guide 35 is turned inwardly as shown at 36 to form an annular lip to confine the air flow in close proximity to the burner jet shield 37 which is a bell-shaped member formed with a nonround tubular portion 38 that fits over the jet 31 and permits a small amount of air to pass upwardly therethrough. A plate 40 closes the bell over the top of the jet 31 and is provided with an axial hole 41 somewhat smaller than the head of the jet. These parts of the burner are fully disclosed and described in the aforementioned patent.

The air guide 35 is mounted axially of the fire pot 7 and the latter is closed at the bottom except for the clearance between the inturned lip 36 and the shield 37.

The liquid fuel pipe 30 is supported by the clamping block 42 which is secured to the underside of the closure lid 43 which has a raised central portion 44 that fits the hole 45 in the bottom of the wind box and disposed in axial alignment with the opening 34. Oppositely projecting lugs 46 are fixed to the lid 43 and are arranged to be locked under the bridge strips 47 on opposite sides of the hole 45 as shown in dotted lines in Fig. 2. Thus by using the pipe 30 as a handle the lid 43 may be inserted in place and turned ninety degrees to swing the lugs 46 under the bridge locking strips 47 and support the burner in the fire pot 7. The lid 43 is provided with a longitudinally disposed slot 48 through which the pipe 30 extends together with the insulator 50 carrying the spark ignitor 51 which is held in fixed relation adjacent the shield 37 and is supplied with electrical energy by the wire 52 from a suitable spark coil. The insulator 50 is rigidly fastened to the pipe 30 by means of the clamp 53 so as to maintain the spark ignitor in fixed position relative to the burner. A plate 54 fitting around the insulator 50 and the pipe 30 and closing the open space of the slot 48 prevents air from leaking from the wind box.

The air being driven down the hood 33 and through the rectangular box 14 would not be driven uniformly up through the guide 35 unless the baffle members 55 and 56 are placed as shown in Figs. 1 and 2. The baffle 55 is materially wider than the baffle 56 and they are placed on opposite sides of the longitudinal center of the wind box 14 as shown in Fig. 2 because of the rotation of the blower 23 which is counter-clockwise when viewed from the left of the drawing. The baffle 55 is positioned further from the burner than the baffle 56 but both baffles extend to substantially the top of the wind box. With this baffle arrangement the long rectangular wind box provides a uniform distribution of the air up through the air guide 35. If the wind box was shortened this baffle arrangement would not properly function and it has been found necessary to maintain the long wind box to obtain the proper flow of air.

Even though the air is uniformly discharged up through the guide 35 the jet 31 produces an unbalanced flame because of the non-uniform discharge of fuel from the burner jet 31. The shield

37 deflects the air radially, creating a rolling turbulent action with the fire pot 7 to shape the burning and nonburning atomized fuel into a vortex, the axle of which is a closed curve. The fire belches up from the rolling vortex and heats the liquid solution in the coils. Owing to the fact that the cold liquid solution coil 6 engages the sheet metal fire bowl 7 the latter is prevented from burning up.

If the flame is not centered within the coils 8 the clamping screw 65 of the clamp block 42 may be loosened and the burner repositioned within the air guide 35 to properly locate the flame. The burner may be moved longitudinally of the slot 48 or the horizontal section of the pipe 30 may be rotated in either direction. Thus the nozzle may be adjusted in any direction to centrally position the flame. The clamping screw 65 on the block 42 is again tightened on the horizontal section of the pipe 30 to maintain this adjusted position. The spacing between the spark electrode 51 and the shield 37 is properly gauged to provide a continuous spark therebetween and the slot 48 in the lid 43 is not sufficiently long to produce a shorter gap between the electrode and the air guide. This insures the proper functioning of the ignition system.

This arrangement not only permits the flame to be properly centered within the heating coils 30 but also permits the burner to be readily withdrawn for cleaning and inspection without disturbing the electrical and the fluid circuits which is a material advantage in this spray generator.

The upper end of the fire pot 7 is provided with an inwardly projecting corrugated flange 57. The top of the corrugations of this flange slopes at an angle of approximately forty-five degrees and aside from aiding to produce the vortex of the burning and unburned turbulent fuel it catches any stray droplets of oil and holds them in the flame where they are burned rather than permit them to drop down on the outside of the fire pot.

The bottom 58 of the fire pot has a central opening 62 radially spaced from the air guide 35 and the bottom 59 of the combustion chamber is fixed to the air guide which has clearance through the hole in the wind box 14. A series of small holes 63 are made in the air guide at the upper surface of the combustion chamber floor 59 for the purpose of permitting any fuel that may collect inside or outside of the fire pot to flow to the air guide and drain through this series of holes where it is permitted to drop to the lid 43 and be retained within the upwardly extending annular flange 60. This stray fuel may pass from the lid through the pipe 61 to floor underneath the spray generator. In this manner the stray fuel is immediately directed out of the machine and is not permitted to collect or stray to other parts of the machine where it may catch on fire and burn up the machine.

I claim:

1. In a burner structure the combination of a wind box closed at its ends, a blower arranged to force air into the wind box, a combustion chamber having a floor and mounted on top of the wind box intermediate of the ends of the latter, a fire pot mounted on the floor concentrically within the combustion chamber, an open ended air guide secured to the floor of the combustion chamber and extending from the wind box into the fire pot, means defining an opening in the bottom of the wind box in alignment with the air guide, a removable lid closing said opening;

a burner mounted on the lid and projecting up through the air guide into the fire pot and having a deflector which produces a flame in the shape of an annular vortex, and means to adjust the burner relative to the lid to center the flame within the fire pot.

2. The structure of claim 1 which also includes a pair of baffles within the wind box extending the full depth of the wind box and parallel to the transverse axis thereof and positioned on opposite sides of the lid with respect to the transverse and longitudinal axes of the wind box.

3. The structure of claim 1 which also includes a bottom of the fire pot, means defining an opening in the fire pot bottom, means defining a drainage opening through the air guide to the combustion chamber adjacent the bottom thereof, said openings directing any stray fuel from the burner to the wind box, and means in the wind box to collect and discharge the stray fuel from the wind box.

4. The structure of claim 1 which also includes an ignition electrode mounted in fixed relation to the burner and adjustable therewith.

5. In a burner structure the combination of a wind box, a combustion chamber mounted on the wind box and open at its upper end, a fire pot mounted within the combustion chamber, an open ended air guide extending from the wind box into the fire pot, means defining an opening in the bottom of the wind box aligned with the air guide, a lid to cover the opening, a burner supported on the lid and extending into the fire pot through the air guide, a clamp on the lid for supporting the burner thereon, and radially adjustable means on the lid whereby the burner may be adjusted radially of the fire pot to center the flame therein when the clamp is loosened.

6. In a burner structure, the combination of an enclosed combustion chamber vented for the discharge of products of combustion, a tubular fire pot open at one end and mounted in the combustion chamber, an open ended tubular air guide extending concentrically into the fire pot for directing an air blast thereinto, a fuel line extending into the air guide, an atomizing fuel burner nozzle on the end of the fuel line, a bell deflector mounted on the nozzle, and an inturned flange around the opening of the fire pot, the bell deflector being spaced slightly from the pipe and nozzle to cooperate with the air guide and the inturned flange whereby the stray droplets of atomized fuel impinge on the inturned flange.

7. In a burner structure, the combination of an enclosed combustion chamber vented for the discharge of products of combustion, a tubular

fire pot open at one end and mounted in the combustion chamber, an open ended tubular air guide extending concentrically into the fire pot for directing an air blast thereinto, a fuel line extending into the air guide, an atomizing fuel burner nozzle on the end of the fuel line, a bell deflector mounted on the nozzle, an inturned flange around the opening of the fire pot, and an inturned flange on the end of the air guide, the bell deflector being spaced slightly from the pipe and nozzle to cooperate with the flange on the air guide and the flange on the fire pot to produce an annular vortex of air and atomized fuel that extends from the bell deflector to the flange on the fire pot and permits the stray droplets of atomized fuel to impinge on the inturned flange of the fire pot.

8. In a burner structure, the combination of a wind box, a combustion chamber mounted on the wind box and open at its upper end, a fire pot mounted within the combustion chamber, an inturned annular corrugated flange on the upper end of the fire pot, an open-ended air guide extending from the wind box into the fire pot, means defining an opening in the bottom of the wind box aligned with the air guide, a lid to cover the opening, a burner supported on the lid and extending into the fire pot through the air guide, means on the lid for supporting the burner, and radially adjustable means on the lid whereby the burner may be adjusted radially of the fire pot to center the flame therein and permit the stray droplets of atomized fuel to impinge on the inturned corrugated flange.
